LABEL AFFIXING MACHINE

Vinecent Lobasso, New York, N. Y.

Application August 19, 1949, Serial No. 111,138

10 Claims. (Cl. 216—57)

1

This invention relates to improvements in label affixing machines and, more especially, to improvements in label affixing machines for applying labels circumferentially about the body of easily deformable articles such as balls of yarn, twine, and the like.

In my Patent No. 2,504,993, issued April 25, 1950, there is disclosed and claimed a machine for applying labels to deformable articles, which machine includes specially designed holder elements preventing deformation of the article during the label affixing operation. The holder elements are mounted on an intermittently actuated chain or wheel conveyor and the articles to be labeled are successively conveyed to a label affixing station where a label may be extended about both the article and the holder element upon which it is supported, the labeled article being subsequently ejected from its holder element by a throwout or ejection mechanism. The present application is concerned with certain improvements over my above identified patent.

One of the objects of the invention is the provision of a machine of the character indicated embodying cushioning means which cooperates with the intermittently rotated conveyor wheel to positively align each holder element at the label affixing station of the machine.

Another object of the invention is the provision of a machine of the character indicated having improved positively acting ejector mechanism for removing the labeled articles from the holder elements.

An additional object of the invention is the provision of cam or guide means fixed to the conveyor wheel and associated with each holder element in such a manner as to automatically provide for closing of the pivoted upper holder arm at the label affixing station of the machine.

A further object of the invention is the provision of an improved holder element having means for positively retaining the applied label in properly adjusted position immediately after the label affixing operation and during the entire interval of operation of the machine between labeling of the article and ejection of the labeled article from its holder element.

The foregoing objects as well as additional objects and advantages of the invention will readily appear in the course of the following detailed description taken in connection with the accompanying drawings which illustrate preferred embodiments of the invention, and wherein:

2

Fig. 1 is a front elevational view of a machine embodying the features of the invention;

Fig. 2 is a fragmentary detail view showing cam means for elevating and lowering the ejector mechanism in removing a labeled article from its respective holder element;

Fig. 3 is a top plan view illustrating the co-operation of the cushioning stop means with the conveyor wheel and holder element;

Fig. 4 is a sectional view of a preferred form of cushioning means or air piston;

Fig. 5 is a similar view of another form of resilient cushioning means;

Fig. 6 is an elevational view illustrating the operation of the ejector mechanism;

Fig. 7 is a fragmentary detail view illustrating an adjustable arrangement for variably tensioning the counterweight of each holder element against the conveyor wheel;

Fig. 8 is a fragmentary front elevation of a modified form of label affixing machine;

Fig. 9 is a view similar to Fig. 8 illustrating the action of the trip mechanism;

Fig. 10 is a fragmentary detail plan view further illustrating the operation of the trip mechanism; and

Fig. 11 is a sectional view taken substantially on line 11—11 of Fig. 10.

The device of the present invention includes an intermittently actuated conveyor system including a plurality of individual holder elements upon which the deformable articles to be labeled may be supported. Each article supported on a respective holder element is conveyed in a step-wise manner to a label affixing station where a label is extended about both the article and the holder arms during the rest period of the conveyor. In one embodiment of the invention each holder element is provided with an auxiliary

pivoted retaining member which is normally urged against the upper tiltable holder arm. Trip means are provided in order to assure automatic elevation of the auxiliary retaining member when a given holder element is disposed at the label affixing station of the machine so that the label may be properly and unobstructedly applied about the article and the main upper and lower holder arms. After the label has been applied and the labeled article on its holder element moves away from the affixing station, the auxiliary holding member operates to retain the affixed label in adjusted position during the interval of rotation of the conveyor wheel between the label affixing station and the ejector station

of the machine. The mechanism for extending,

overlapping and securing the label is described in my Patent No. 2,179,264, issued November 7, 1939, and will not be detailed here since it does not form the subject matter of the present invention.

A major feature of the present invention resides in the provision of cushioning stop means reciprocated synchronously with the rotation of the conveyor wheel in such a manner as to positively align each holder element at the label affixing station. This stop means conveniently takes the form of a reciprocating member or bar resiliently mounted to cushion the impact of the conveyor wheel incident to the cessation of rotation of the conveyor wheel upon successive contact of said stop member with stop lugs suitably disposed on said conveyor wheel adjacent each holder element.

The ejector mechanism of the device has been improved over that disclosed in my co-pending application to assure positive and foolproof removal of the labeled articles from their respective holder elements. The foregoing features as well as additional features of the invention will now be described in greater detail with reference to the accompanying drawings.

Referring first to the embodiment of the invention illustrated in Figs. 1-7 of the drawings, the device includes a conveyor element or wheel 10 rotatably mounted in a bearing 11 secured to a frame 12. A plurality of holder elements 13 are rotatably mounted on the rim of wheel 10 and said holder elements are constantly maintained in vertical or upright position as the wheel rotates by means of a counterweight 14 secured to the rear end of the mounting arm 15 of each holder element 13. As shown in Fig. 7, each counterweight 14 may be adjustably tensioned against the rear surface of conveyor wheel 10 by means of a plunger 16 resiliently urged into frictional engagement against said conveyor wheel by means of a spring 17, the pressure of which may be regulated by an adjusting screw 18.

In addition to the mounting arm 15 which is rotatably mounted with respect to the conveyor wheel 10, each holder element 13 comprises a main plate 19 fixed to said mounting arm, a lower adjustable arm 20 slidably mounted on said main plate and a tiltable upper arm 21 pivotally mounted on said main plate. Mounting arm 15 is further provided with a slidable spacer or piston 22 for varying the effective depth of each holder element in order to accommodate articles of varying size.

The tiltable upper arm 21 of each holder element is normally urged to closed, substantially horizontal position by means of a light tension spring (not shown). Said upper arm also carries at its rear end a roller 23 adapted to be engaged by a leaf spring or the like associated with the stop means of the device in order to further assure horizontal disposition of the upper arm in closed position at the label affixing station, as shown in Figs. 1 and 3, and as will be more fully described hereinbelow.

Holder elements 13 loaded with yarn balls or other deformable articles are successively conveyed to the label affixing station, designated L in Fig. 1, by imparting intermittent movement to conveyor wheel 10 so that a loaded holder element will be disposed at label affixing station L during the rest period of the conveyor. A label is extended circumferentially about the article and the holder arms 20 and 21, the ends of the

label are first overlapped and then secured together at the label affixing station L. The application of the label may be accomplished substantially in the manner disclosed in my Patent No. 2,179,264. Intermittent movement may be imparted to the conveyor wheel 10 in any desired manner, as by means of a reciprocating hook successively engageable with each of a plurality of notches 24 uniformly spaced about the periphery of wheel 10 in accordance with the arrangement described in my previously identified co-pending application.

An important feature of the invention resides in the provision of resilient cushioning stop means reciprocated synchronously with the rotation of conveyor wheel 10 in such a manner as to positively align each holder element 13 at the label affixing station L. This stop means conveniently takes the form of a reciprocating member or bar 25 arranged to periodically abut stop lugs 26 suitably disposed on conveyor 10, adjacent each holder element 13, said stop member being resiliently mounted to cushion the impact of the conveyor wheel. As clearly shown in Figs. 1 and 3, stop member 25 is pivotally mounted at 25a on a reciprocable base element or carrier 27 retained in a slide bearing 28 secured to the frame of the machine. Reciprocatory motion is imparted to carrier 27 by means of a lever 29 pivoted to the frame 12 at 30, said lever having an upper slotted end 29a pivoted to one end of carrier 27. Lever 29 carries a follower 31 engaged within the camway 32 of a continuously rotating camwheel 33 mounted on shaft 34. Shaft 34 is preferably the driveshaft of the machine and may also carry a crank-wheel (not shown) by means of which intermittent rotation is imparted to conveyor wheel 10 in accordance with the arrangement described in my co-pending application. In the preferred embodiment of the invention stop member 25 is pivoted intermediate its ends at 35 to the upper end of a piston 36 retained in an air cylinder 37 mounted on carrier 27 adjacent conveyor wheel 10. As best shown in Fig. 4, air cylinder 37 is provided with an intake port 38 controlled by an intake ball-valve 39 and spring 40. An outlet passageway 41 connects the air chamber of cylinder 37 with an outlet port 42 and the rate of air discharge from the cylinder may be regulated by means of an adjustment screw 43 which bears against a suitable tension spring 44 biasing the outlet ball-valve 45 against the discharge end of outlet passageway 41. A suitable washer 46 is secured to the inner end of piston 36 in order to assure an airtight seal within air cylinder 37. By reason of the described arrangement an adjustable cushioning effect may be attained for resiliently mounted stop member 25 depending upon the size and mass of conveyor wheel 10 and the size and mass of the articles being labeled.

During the retraction of carrier 27 stop member 25 is rotated in a clockwise direction about its pivot 35 to the elevated position illustrated in broken outline in Fig. 1 preparatory to the step-wise advancement and the cushioned cessation of rotation of conveyor wheel 10 which results in the alignment of another loaded holder element 13 at the labeling station L. This resetting motion of stop member 25 is achieved by means of an angularly inclined deflector plate 50 secured to the frame of the machine and arranged to abut a roller 51 carried at the outer end of said stop member. A leaf spring 52 may also be secured to a lug 53 of stop member 25 for engaging the roller

23 of the tiltable upper arm 21 of each holder element at the labeling station L in order to assure positive retention of the article being labeled by the holder element during the label affixing operation. In order to prevent back motion of the conveyor wheel a detent hook or pawl 54 is mounted on the frame of the machine and spring urged into successive engagement with each of the stop notches 24 uniformly spaced about the periphery of said conveyor wheel.

It will be understood that the stepwise advancement of each loaded holder element 13 toward the labeling station L will be accompanied by the advancement of the sliding carrier 21 and the elevated stop member 25 until a respective stop lug 26 on conveyor wheel 10 abuts the inner end of stop member 25. Accordingly, the periodic cessation of rotation of conveyor wheel 10 will be cushioned by virtue of the resilient mounting of stop member 25 with the downwardly urged air piston 36 being retarded by a gradually expendable air column controlled by the outlet valve 45. Fig. 5 illustrates a somewhat simpler arrangement of cushioning device wherein the piston 36 is retarded mechanically by means of a compression spring 55 rather than by means of air compression. It will be understood that alternative resilient means may be employed for cushion stop member 25.

An improved throwout or ejection mechanism 60 is provided for removing labeled articles from holder elements 13 after labels have been applied at the labeling station L, said ejection mechanism being operative at a point remote from the labeling station and being positive and fool-proof in operation and greatly contributing to the smooth and uninterrupted functioning of the device. The ejection station has been designated E in Fig. 1. Ejection mechanism 60 includes a slidable member or carriage 61 mounted upon a pair of rail supports 62 slidably secured to the frame of the machine. Carriage 61 preferably comprises as an integral structure a pair of side members 61a, a central sleeve-guide 61b and a pair of finger cams 61c having upwardly divergent ends 61d. Carriage 61 undergoes reciprocatory motion by means of a cam 63 mounted on a shaft 64 which cam is preferably provided with a helical camway for the reception of a follower 65 carried at the end of a rocking lever 66 pivotally mounted on a bracket 67. The free end of lever 66 is preferably forked, as shown at 68 in Fig. 6, for articulation with the lower end of carriage sleeve-guide 61b. An ejector member 69 is slidably retained in sleeve-guide 61b for reciprocation in a vertical path and is supported at its lower end by means of a laterally offset roller 70 engaged in a guide member 71 fixed to the end of rocking lever 66 pivoted to the frame of the machine intermediate its ends at 73. The opposite end of rocking lever 66 is connected by means of a linkage 74 to a cam lever 75 having a follower 75a constantly urged into engagement against the periphery of a cam 76 by means of a spring 77, as clearly shown in Fig. 2. Ejector member 69 carries at its upper end a cross member 78 upon which are pivotally mounted a pair of ejector arms 79 normally urged inwardly toward each other in the position of Fig. 1 by means of a tension spring 80. The lower ends of ejector arms 79 carry followers or pins 81 (see Fig. 6) engageable against the finger cams 61c of carriage 61 during the depression or retraction of ejector member 69. By reason of the described ar-

rangement it will be understood that the ejector member 69 will travel in a substantially rectilinear path determined by the simultaneous rotation of cams 63 and 76. In a single cycle of operation carriage 61 and ejector member 69 will first move rearwardly toward the holder element which is disposed at the ejection station E during the rest period of the conveyor wheel 10. The ejector member 69 will then be elevated to the position illustrated in full lines in Figs. 1 and 6 whereupon the follower pins 81 of ejector arms 79 will be free of engagement with the divergent ends 61d of finger cams 61c and said arms will approach each other preparatory to the ejection of the labeled article on the holder element 13 at the ejection station E, which occurs upon the return stroke of carriage 61. The cycle is completed at the limit of travel of the return stroke of carriage 61 whereupon ejector member 69 and guide member 71 carried by rocking lever 72 are restored to their depressed or retracted positions illustrated in broken lines in Figs. 1 and 6. It will be understood that the retraction of ejector member 69 following the operative forward ejection stroke of carriage 61 will be accompanied by the separation of the ejector arms 79 preparatory to the ejection of the next labeled article from its respective holder element.

Figs. 8 to 11 illustrate a modified form of the invention wherein conveyor wheel 85 is mounted on frame 86 for intermittent rotation in a manner similar to that described for the initial embodiment of Figs. 1 to 7. A plurality of holder elements 87 (see Fig. 11) are freely swingable with respect to conveyor wheel 85. Each holder element comprises a mounting arm 88, a main plate 89 fixed to said mounting arm, a lower adjustable arm 90 slidably mounted on said main plate and a tiltable upper arm 91 pivotally mounted on said main plate. Said upper arm carries at its rear end a roller 92 adapted to be engaged at the labeling station L by a respective fixed cam 93 suitably secured to conveyor wheel 85. As best shown in Fig. 11 each cam 93 is rigidly mounted on a fixed sleeve 94. Mounting arm 88 extends through fixed sleeve 94, carries at its inner end a counterweight 95 for constantly maintaining each of the holder elements 87 in vertical or upright position as the conveyor wheel is caused to rotate. Mounting arm 88 is further provided with a slidable spacer or piston 96 for varying the effective depth of each holder element in order to accommodate articles of varying size. Each holder element is further provided with an auxiliary pivoted retaining member or hold-down bar 97 which is normally urged against the upper holder arm 91, as by means of a spring 98, and which serves to retain the applied label in properly adjusted position during the interval of rotation of conveyor wheel 85 from the moment of application of a label around a particular article until the ejection of the labeled article from its holder element, as will be more fully described hereinbelow.

Cushioning stop means similar in structure and operation to that described for the initial embodiment are also provided for aligning each holder element 87 at the label affixing station. Stop member or bar 99 is arranged to periodically abut stop lugs 100 suitably disposed on conveyor 85 adjacent each holder element 87, said stop member being resiliently mounted to cushion the impact of the conveyor wheel stop lugs incident to the cessation of rotation of the conveyor wheel.

As best shown in Figs. 8 and 10, stop member 99 is pivotally mounted at 101 on a reciprocable carrier 102 retained in a slide bearing 103, which carrier may be actuated in a manner similar to that described for the initial embodiment. Said stop member is also pivoted intermediate its ends at 104 to the upper end of a piston 105 retained in an air cylinder 106 mounted on carrier 102 adjacent conveyor wheel 85. Upon retraction of carrier 102, stop member 99 is elevated or reset by means of a resetting bar 107 which has a common pivot 101 with said stop member. Resetting bar 107 is further provided with a bifurcated end 107a for pivotal engagement with a laterally offset pin 108 secured to the upper end of piston 105. The opposite or outer end of said resetting bar carries a roller 107b arranged to abut a suitably angularly inclined deflector plate 109 secured to the frame of the machine. Upon retraction of carrier 102 both the resetting bar 107 and the stop member 99 are rotated to elevated position about their common pivot 101 in a clockwise direction (as seen in Figs. 8 and 9) and piston 105 is simultaneously elevated to operative position as shown in Fig. 9.

In order to allow the unobstructed application of a label 110 about the deformable article supported on its holder element 87 at the labeling station during the rest period of conveyor wheel 85, trip means are provided for raising hold-down bar 97 out of contact with upper holder arm 81, as shown in broken outline in Fig. 11. For this purpose, a trip member 111 is pivotally suspended at 112 from one end of a rocker arm 113 pivotally secured at 114 to a frame bracket 115, said rocker arm being actuated in any desired manner as by means of a cam lever 116 slidable in a bearing support 117 and controlled by a cam 118. A biasing lever 119 is pivoted to the lower end of trip member 111 at 120 and extends upwardly therefrom to be supported by free frictional engagement against laterally offset pin 108 of piston 105. Adjacent pivot 120 biasing lever carries a leaf spring 121 for resiliently urging trip member 111 into its operative position in order to elevate hold-down bar 97 to the broken line position of Fig. 11. The required elevation of hold-down bar 97 is conveniently effected by the provision on trip member 111 of an abutment shoulder 111a which acts against a rearward extension 97a of said hold-down bar when said trip member is actuated in a downward direction by rocker arm 113 and cam 118.

In order to prevent back motion of the conveyor wheel 85 and to assure positive alignment of each holder element 87 at the labeling station of the machine, a detent hook or pawl 122 is mounted on a rocker arm 123 substantially parallel to the rear end of rocker arm 113. Rocker arm 123 is pivotally mounted at 124 on a frame bracket 125 which is preferably located a shorter distance from conveyor wheel 85 than frame bracket 115. Rocker arms 113 and 123 are interconnected at their outer ends by a somewhat flexible bridge member 126, thereby permitting sufficient torsional movement to compensate for the differential disposition of the pivots 114 and 124 of rocker arms 113 and 123 respectively. Detent hook 122 is spring urged into successive engagement with each of the stop notches 127 uniformly spaced about the periphery of conveyor wheel 85. Clockwise rotation of rocker arm 123 about the pivot 124 will cause detent hook 122 to advance slightly to meet and engage a respective stop notch 127, thereby positively

maintaining a respective holder element 87 in properly aligned position at the labeling station of the machine during the rest period of the conveyor.

5 At the ejector station of the machine it is again necessary to elevate hold-down bar 97 to permit removal of a labeled article from its holder element. For this purpose a fixed ejector trip member 128 is mounted on a fixed support 129 forwardly of conveyor wheel 85 (see Fig. 8) and suitably disposed in order to abut the rearward extension 97a of hold-down bar 97. The ejector mechanism may be substantially the same in structure and operation as that described for 10 the initial embodiment of the invention.

Since certain modifications may be made in the label affixing machine of the present invention without departing from the scope thereof, it is intended that all matter contained in the 20 foregoing description and shown in the accompanying drawing be interpreted merely as illustrative and not in a limiting sense.

What is claimed is:

1. In a label affixing machine of the type having 25 means for applying labels circumferentially about the body of an article, an intermittently operated conveyor having a plurality of holder elements rotatably mounted thereon for retaining articles to be labeled, reciprocating stop means synchronized with the rotation of said conveyor for periodically and resiliently arresting the motion of said conveyor in order to consecutively dispose each of said holder elements in labeling position and ejection means operable 30 to remove a labeled article from its supported position on a holder element at a point in the movement of said conveyor remote from said label-applying means, said ejection means having a substantially rectilinear path and having 35 a pair of pivoted ejector arms alternately movable toward and away from each other upon reversal of the vertical direction of travel of said ejection means.

2. In a label affixing machine of the type having 45 means for applying labels circumferentially about the body of an article, an intermittently operated conveyor having a plurality of holder elements rotatably mounted thereon for retaining articles to be labeled, said conveyor having a plurality of spaced stop lugs disposed thereupon adjacent each of said holder elements, a reciprocating stop member synchronized with the rotation of said conveyor for successively and resiliently abutting each of said stop lugs in order to 50 consecutively dispose each of said holder elements in labeling position and ejection means operable to remove a labeled article from its supported position on a holder element at a point in the movements of said conveyor remote from said label-applying means, said ejection means having a substantially rectilinear path and having 55 a pair of pivoted ejector arms alternately movable toward and away from each other upon reversal of the vertical direction of travel of said ejection means.

3. In a label affixing machine of the type having 60 means for applying labels circumferentially about the body of an article, an intermittently operated conveyor having a plurality of holder elements rotatably mounted thereon for retaining articles to be labeled, said conveyor having a plurality of spaced stop lugs disposed thereupon adjacent each of said holder elements, a reciprocating carrier mounted for motion toward and away 65 from said conveyor, a stop member pivotally

mounted on said carrier for successively and resiliently abutting each of said stop lugs in order to consecutively dispose each of said holder elements in labeling position, a resiliently supported piston mounted on said carrier, said stop member being pivotally connected to the free end of said piston, and a fixed deflector member adapted to abut the outer end of said stop member upon retraction of said carrier for restoration of said stop member and piston to operative elevated position.

4. In a label affixing machine of the type having means for applying labels circumferentially about the body of an article, an intermittently operated conveyor having a plurality of holder elements rotatably mounted thereon for retaining articles to be labeled, said conveyor having a plurality of spaced stop lugs disposed thereupon adjacent each of said holder elements, a reciprocating carrier mounted for motion toward and away from said conveyor, a stop member pivotally mounted on said carrier for successively and resiliently abutting each of said stop lugs in order to consecutively dispose each of said holder elements in labeling position, a resiliently supported piston mounted on said carrier, said stop member being pivotally connected to the free end of said piston, a fixed deflector member adapted to abut the outer end of said stop member upon retraction of said carrier for restoration of said stop member and piston to operative elevated position, and ejection means operable to remove a labeled article from its supported position on a holder element at a point in the movement of said conveyor remote from said label-applying means, said ejection means having a substantially rectilinear path and having a pair of pivoted ejector arms alternately movable toward and away from each other upon reversal of the vertical direction of travel of said ejection means.

5. In a label affixing machine of the type having means for applying labels circumferentially about the body of an article, an intermittently operated conveyor having a plurality of holder elements rotatably mounted thereon for retaining articles to be labeled, said conveyor having a plurality of spaced stop lugs disposed thereupon adjacent each of said holder elements, a reciprocating carrier mounted for motion toward and away from said conveyor, a stop member pivotally mounted on said carrier for successively and resiliently abutting each of said stop lugs in order to consecutively dispose each of said holder elements in labeling position, said carrier being provided at its inner end with an air cylinder having a piston protruding externally thereof, said stop member being pivotally connected to the free end of said piston, and a fixed deflector member adapted to abut the outer end of said stop member upon retraction of said carrier for restoration of said stop member and piston to elevated operative position.

6. In a label affixing machine of the type having means for applying labels circumferentially about the body of an article, an intermittently operated conveyor having a plurality of holder elements rotatably mounted thereon for retaining articles to be labeled, said conveyor having a plurality of spaced stop lugs disposed thereupon adjacent each of said holder elements, a reciprocating carrier mounted for motion toward and away from said conveyor, a stop member pivotally mounted on said carrier for successively and resiliently abutting each of said stop lugs in order to consecutively dispose each of said holder

elements in labeling position, said carrier being provided at its inner end with an air cylinder having a piston protruding externally thereof, said stop member being pivotally connected to the free end of said piston, a fixed deflector member adapted to abut the outer end of said stop member upon retraction of said carrier for restoration of said stop member and piston to elevated operative position, and ejection means operable to remove a labeled article from its supported position on a holder element at a point in the movement of said conveyor remote from said label-applying means, said ejection means having a substantially rectilinear path and having a pair of pivoted ejector arms alternately movable toward and away from each other upon reversal of the vertical direction of travel of said ejection means.

7. In a label affixing machine of the type having means for applying labels circumferentially about the body of an article, an intermittently operated conveyor having a plurality of holder elements rotatably mounted thereon for retaining articles to be labeled, each holder element comprising a pair of opposed upper and lower arms contacting portions of the peripheral surface of the article, the upper arm of each holder element being tiltable upwardly to open position, said conveyor being provided with fixed cam means adjacent each of said holder elements adapted for elevating said tiltable upper arm to closed operative position in the labeling position of the holder element, an auxiliary pivoted hold-down arm normally spring-urged into contact against said upper arm for retaining the applied label in position, and a trip member adapted to elevate said hold-down arm in the labeling position of each holder element during the rest period of the conveyor.

8. In a label affixing machine of the type having means for applying labels circumferentially about the body of an article, an intermittently operated conveyor having a plurality of holder elements rotatably mounted thereon for retaining articles to be labeled, each holder element comprising a pair of opposed upper and lower arms contacting portions of the peripheral surface of the article, the upper arm of each holder element being tiltable upwardly to open position, said conveyor being provided with fixed cam means adjacent each of said holder elements adapted for elevating said tiltable upper arm to closed operative position in the labeling position of the holder element, an auxiliary pivoted hold-down arm normally spring-urged into contact against said upper arm for retaining the applied label in position, a trip member adapted to elevate said hold-down arm in the labeling position of each holder element during the rest period of the conveyor, reciprocating stop means synchronized with the rotation of said conveyor for periodically and resiliently arresting the motion of said conveyor in order to consecutively dispose each of said holder elements in labeling position, ejection means operable to remove a labeled article from its supported position on a holder element at a point in the movement of said conveyor remote from said label-applying means, said ejection means having a substantially rectilinear path and having a pair of pivoted ejector arms alternately movable toward and away from each other upon reversal of the vertical direction of travel of said ejection means, and fixed abutment means adapted to elevate said hold-down arm in the ejection position of each

holder element in order to allow removal of the labeled article by said ejection means.

9. In a label affixing machine of the type having means for applying labels circumferentially about the body of an article, an intermittently operated conveyor having a plurality of holder elements rotatably mounted thereon for retaining articles to be labeled, each holder element comprising a pair of opposed upper and lower arms contacting portions of the peripheral surface of the article, the upper arm of each holder element being tilttable upwardly to open position, said conveyor being provided with fixed cam means adjacent each of said holder elements adapted for elevating said tilttable upper arm to closed operative position in the labeling position of the holder element, an auxiliary pivoted hold-down arm normally spring-urged into contact against said upper arm for retaining the applied label in position, a trip member adapted to elevate said hold-down arm in the labeling position of each holder element during the rest period of the conveyor, said conveyor having a plurality of spaced stop lugs disposed thereupon adjacent each of said holder elements, a reciprocating carrier mounted for motion toward and away from said conveyor, a stop member pivotally mounted on said carrier for successively and resiliently abutting each of said stop lugs in order to consecutively dispose each of said holder elements in labeling position, a resiliently supported piston mounted on said carrier, said stop member being pivotally connected to the free end of said piston, a fixed deflector member adapted to abut the outer end of said stop member upon retraction of said carrier for restoration of said stop member and piston to operative elevated position, ejection means operable to remove a labeled article from its supported position on a holder element at a point in the movements of said conveyor remote from said label-applying means, said ejection means having a substantially rectilinear path and having a pair of pivoted ejector arms alternately movable toward and away from each other upon reversal of the vertical direction of travel of said ejection means, and fixed abutment means adapted to elevate said hold-down arm in the ejection position of each holder element in order to allow removal of the labeled article by said ejection means.

10. In a label affixing machine of the type having means for applying labels circumferentially about the body of an article, an intermittently operated conveyor having a plurality of holder elements rotatably mounted thereon for retaining

articles to be labeled, each holder element comprising a pair of opposed upper and lower arms contacting portions of the peripheral surface of the article, the upper arm of each holder element being tilttable upwardly to open position, said conveyor being provided with fixed cam means adjacent each of said holder elements adapted for elevating said tilttable upper arm to closed operative position in the position of the holder element, an auxiliary pivoted hold-down arm normally spring-urged into contact against said upper arm for retaining the applied label in position, a trip member adapted to elevate said hold-down arm in the labeling position of each holder element during the rest period of the conveyor, said conveyor having a plurality of spaced stop lugs disposed thereupon adjacent each of said holder elements, a reciprocating carrier mounted for motion toward and away from said conveyor, a stop member pivotally mounted on said carrier for successively and resiliently abutting each of said stop lugs in order to consecutively dispose each of said holder elements in labeling position, said carrier being provided at its inner end with an air cylinder having a piston protruding externally thereof, said stop member being pivotally connected to the free end of said piston, a fixed deflector member adapted to abut the outer end of said stop member upon retraction of said carrier for restoration of said stop member and piston to elevated operative position, ejection means operable to remove a labeled article from its supported position on a holder element at a point in the movement of said conveyor remote from said label-applying means, said ejection means having a substantially rectilinear path and having a pair of pivoted ejector arms alternately movable toward and away from each other upon reversal of the vertical direction of travel of said ejection means, and fixed abutment means adapted to elevate said hold-down arm in the ejection position of each holder element in order to allow removal of the labeled article by said ejection means.

VINCENT LOBASSO.
